CLAIM

The ornamental design for a washing and cleaning machine, as shown and described.

DESCRIPTION

FIG. 1 is a top perspective view of a washing and cleaning machine in a closed state with its cover on, showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a perspective view of the washing and cleaning machine of FIG. 1 in an open state with the cover removed; and,

FIG. 10 is a perspective view of the washing and cleaning machine of FIG. 1 in a usable state with the cover removed. The broken lines shown in the drawings illustrate portions of the washing and cleaning machine that form no part of the claimed design.
